UNITED STATES PATENT OFFICE.

ANDRÉ VARAUD, OF VESENAZ, NEAR GENEVA, SWITZERLAND, ASSIGNOR TO SOCIÉTÉ ANONYME D'HORLOGERIE ET BIJOUTERIE DE GENÈVE, OF GENEVA, SWITZERLAND, A COMPANY OF SWITZERLAND.

TIME INDICATOR.

Original application filed August 11, 1920, Serial No. 402,920. Divided and this application filed November 5, 1921, Serial No. 513,120.

To all whom it may concern:

Be it known that I, ANDRÉ VARAUD, watchmaker, a citizen of France, residing at Vesenaz, near Geneva, Canton of Geneva, in 5 the Confederation of Switzerland, have invented certain new and useful Improvements in Time Indicators (for which I have filed applications in Switzerland March 29, 1919, Apr. 29, 1919, and Oct. 29, 1919), of which

10 the following is a specification.

This invention has for its object a time indicator of the type in which a movable dial bearing chronometric indications arranged circularly moves always in the same 15 direction under a fixed dial having at least one opening in it, and this application is a division of my copending application, Serial No. 402,920, filed August 11, 1920, for Letters Patent for an improvement in time indicators.

This invention is represented in the accompanying drawings which show as examples thereof, several constructional forms, all adapted to already known sizes of 20 watches, clocks or alarms.

Figure 1 is an elevation, natural size, of a first working form.

Figure 2 is an elevation thereof on a larger scale the case and the fixed dial being removed.

Figures 3 and 4 are detail views thereof showing detached in elevation and axial section the escapement member of the movable dial.

Figures 5 and 6 are likewise detail views showing detached in elevation and axial section the operating member of the movable dial.

Figure 7 is a last detail view thereof showing detached the movable dial in transverse section.

Figures 8 to 10 relate to the second constructional form.

Figure 8 being an elevation natural size. 45 Figure 9 an elevation on a larger scale, the case and the fixed dial being removed, and

Figure 10 a transverse section on a larger scale on the line 10—10 of Figure 9 on the 50 front face of the plate.

Figures 11 to 13 relate to the third form.

Figure 11 being an elevation with part of the case and of the fixed dial broken away.

Figure 12 a transverse section on the broken line 12—12 of Figure 11, and

55 Figure 13 is a detail view showing from underneath the central escape wheel.

Figures 14 to 16 are similar respectively to Figures 11 and 13 and relate to the fourth form.

60 Figure 17 is a detail view showing detached a modification of the spring which actuates the escape wheel.

Figures 1 to 17 show four constructional forms of the subject matter of the invention applied to the ordinary sized watch or

alarm already known utilizing a cylinder escapement. In the first form (see Figs. 1 to 7) the movable dial is constituted by a thin ring b^1 carrying circularly 24 indications 70

of hours numbered from 24 to 1. This ring slides externally in a circular slide constituted by small cheeks c^3 carried by the dust trap ring 3 fixed to the plate 1. Inside this ring b^1 carries 24 teeth arranged alternately

75 at different levels so as to constitute a series of teeth y of 12 teeth in the plane of the ring and by bending back another series of teeth z of 12 teeth above this level. These

two series of teeth are in constant engagement with a disc d which is mounted freely

80 on a carrier screw d^1 screwed into the plate 1 and which carries four pins d^8 arranged perpendicularly to the surface of the disc d . On the collar d^9 of the carrier screw d^1 85 oscillates freely below the disc d a wheel e^{17} which gears with the cannon pinion 5 of the movement of the watch. The ratio

85 of this gear is so chosen that the cannon pinion which makes one complete revolution on itself in one hour, causes this wheel to make $\frac{1}{12}$ of a revolution on itself during the same lapse of time. This wheel e^{17} carries a small pin e^{18} , to which is fixed the outer end of a spiral spring f^2 , the other

90 end of which is fixed under the disc d to a sleeve d^{10} integral with this disc.

The ring b^1 is still in engagement constantly with a cylinder escapement device g which is mounted freely with a wheel g^4 100 with which it is integral, on a carrier screw g^3 likewise screwed into the plate 1. This

wheel g^4 gears with an intermediate wheel i^4 , mounted freely on a carrier screw i^2 which gears with the cannon pinion 5 mounted frictionally on the shaft of the main pinion.

The ratios of gearing are so arranged that the cannon pinion 5 which makes one complete revolution per hour, may cause the cylinder escapement g to make during the same time half a revolution on itself and always in the same direction. This escapement device g has two notches g^1 and g^2 arranged diametrically at different levels opposite the teeth y and z of the ring b .

9 denotes the seconds hand which may be retained without interfering with the rotation of the ring b .

The working of this constructional form is as follows:

20 As long as the ring b^1 is locked by the escapement device g , the solid part of the cylinder being between two consecutive teeth of the ring that is to say, during 59 minutes 59 seconds, the spring f^2 is compressed 25 by the wheel e^{17} driven by the cannon pinion 5.

As soon however as one of the notches g^1 , g^2 comes opposite the corresponding teeth y or z of the ring, this latter being subjected 30 to the motive force stored up by the spring f^2 by the medium of the pin disc d , the escape of a single tooth y or z is produced, which allows of the rotation on itself of the ring by $\frac{1}{24}$ th of a revolution.

35 In the second constructional form (shown in Figs. 8 to 10) the ring b^1 carrying two series of teeth y and z at two different levels, rolls, by means of six rollers c which it carries on its rear face in a groove of circular 40 shape made in the plate 1 of the watch.

The wheel g^4 integral with the escapement device g gears in this form with the minute wheel 6, and the cylinder g rotates on the one hand in a hollow in the plate 1 of the watch and on the other hand in a bridge 11 which covers the minute wheelwork.

The wheel d which drives the ring b^1 carries six pins d^8 instead of four and is actuated by a wheel i^2 mounted freely on the cannon pinion. The spring f^3 is fixed at one of its ends to this wheel i^2 and at the other end to the cannon wheel 8. The working is the same as in the preceding form.

55 Through the opening a^2 appear from noon to midnight the corresponding indications of the old notation of the hours from 1 to 12.

In the third form represented in Figs. 11 to 13 the ring b^1 carries internally a series of teeth 24 of ogival shape which is constantly in engagement with the pinion d . On the front face of this plate 1 is mounted freely on the cannon pinion 5 above the cannon wheel 8 a wheel i^4 provided with two stag-

gered sets of teeth i^5 and i^6 with six teeth in each set. All the teeth in both of these sets gear with the pinion d . The wheel i^4 is hollow internally so as to form a seating for a circular spring f^4 , one of the bent ends f^3 70 of which is connected to the wheel i^4 and the other bent end f^6 to the cannon wheel 8. The teeth i^5 and i^6 are in engagement with a cylinder escapement g which oscillates between the plate 1 and a bridge 12.

In the fourth constructional form represented in Figs. 14 to 16, the hour hand is retained. The movable dial b has only the ring b^1 the indications of which for the hours are numbered 0 to 23. The diameter of the escapement wheel i^4 is smaller so as not to interfere with the seconds hand 9. The spring f^4 which actuates this escapement wheel i^4 is in the form of a spiral which terminates at its two ends f^5 and f^6 in two loops in which engage two pins carried respectively by the escapement wheel i^4 and by the cannon wheel 8.

Fig. 17 shows a modification of the form of this spring f^4 , in which the loop f^5 is replaced by a curved portion and in which the form of the spring is cylindrical.

Instead of having teeth the ring b^1 might be provided with 24 pins arranged vertically towards the surface of the plate 1 which would enter into engagement like the teeth either with the pinion d or with the notched cylinder g .

Having now particularly described and ascertained the nature of my said invention and in what manner the same may be performed, I declare that what I claim is:

1. In a time indicator and in combination with a casing and a motor mechanism, a fixed dial having an opening therein, a revolute dial having chronometric indications thereon visible through the opening in the fixed dial, a cylinder escapement for controlling the movement of the revolute dial, a cannon pinion, and means operated by the cannon pinion for turning the revolute dial a predetermined portion of a revolution when released by the said escapement.

2. In a time indicator and in combination with a casing and a motor mechanism, a fixed dial having an opening therein, a revolute dial having chronometric indications thereon visible through the opening in the fixed dial, a cannon pinion, a cylinder escapement for normally maintaining the revolute dial in a fixed position, means driven by the cannon pinion for actuating the cylinder escapement, and devices also operated by the cannon pinion for turning the revolute dial a predetermined portion of a revolution when released by the said cylinder escapement.

3. In a time indicator and in combination with a casing and a motor mechanism, a

- fixed dial having an opening therein, a revolute dial having chronometric indications thereon visible through the opening in the fixed dial, a cannon pinion, a cylinder escapement for the revolute dial, a gear driven by the cannon pinion, and means actuated by the said gear for engaging and periodically moving the revolute dial a predetermined portion of a revolution when the 10 revolute dial is released by the said cylinder escapement.
4. In a time indicator and in combination with a casing and a motor mechanism, a fixed dial having an opening therein, a revolute dial having chronometric indications thereon visible through the opening in the fixed dial, a cannon pinion, a cylinder escapement for the revolute dial, a gear driven by the cannon pinion, a disk, means 15 for yieldingly connecting the said disk to the said gear, and devices causing the said disk to cooperate with the said revolute dial to move the same a predetermined portion of a revolution when the revolute dial 20 is released by the said cylinder escapement.
5. In a time indicator and in combination with a casing and a motor mechanism, a fixed dial having an opening therein, a revolute dial having chronometric indications 25 thereon visible through the opening in the fixed dial, a cannon pinion, a cylinder escapement for the revolute dial, a gear driven by the cannon pinion, a disk, a spring connecting the said gear and disk, and a plurality of pins extending from the said disk and adapted to engage with a series of internal teeth on the said revolute dial to move the same a predetermined portion of a revolution when the revolute dial is released 30 by the cylinder escapement.
6. In a time indicator and in combination with a casing and a motor mechanism, a fixed dial having an opening therein, a revolute dial having chronometric indications 35 thereon visible through the opening in the fixed dial, a cannon pinion, a cylinder escapement including a barrel having oppositely disposed recesses therein for the passage of staggered teeth on the revolute dial 40 whereby the revolute dial is fixed except when the barrel is in position to permit the said teeth to pass through the said recesses, means for operating the said cylinder escapement from the cannon pinion, and devices also operated from the cannon pinion for turning the said revolute dial a predetermined portion of a revolution when the same is released by the said cylinder escapement.
7. In a time indicator and in combination with a casing and a motor mechanism, a fixed dial having an opening therein, a revolute dial having chronometric indications 45 thereon visible through the opening in the fixed dial, a cannon pinion, an arbor, a gear mounted on the arbor, an intermediate gear meshing with the aforesaid gear and the cannon pinion, a barrel also mounted on the said arbor and having oppositely disposed recesses therein for the passage of sets of staggered teeth on the said revolute dial, and devices also operated by the cannon pinion for turning the movable dial a predetermined portion of a revolution when the said barrel is in position to permit the teeth 50 to pass through the said recesses therein.
8. In a time indicator and in combination with a casing and a motor mechanism, a fixed dial having an opening therein, a revolute dial having chronometric indications 55 thereon visible through the opening in the fixed dial, a cannon pinion, an arbor, a gear mounted on the arbor, an intermediate gear meshing with the aforesaid gear and the cannon pinion, a barrel also mounted on the said arbor and having oppositely disposed recesses therein for the passage of sets of staggered teeth on the said revolute dial, another gear wheel also meshing with the said cannon pinion, a disk, a spring for 60 yieldingly connecting the said disk and the last aforesaid gear wheel, and a plurality of pins carried by the said disk and adapted to engage the said teeth on the revolute dial to move the same a predetermined portion of a revolution when the movement of the revolute dial is made possible by the passage of the teeth through the said recesses in the said barrel.
9. In a time indicator and in combination with a casing and a motor mechanism, a fixed dial having openings therein, a revolute dial having chronometric indications thereon visible through one of the openings in the fixed dial, a revolute ring also having chronometric indications thereon visible through another opening in the fixed dial, a cannon pinion, a cylinder escapement for simultaneously permitting the movement of the revolute dial and the revolute ring, and means also operated by the cannon pinion for simultaneously turning the revolute dial and revolute ring a predetermined portion of a revolution when released by the said escapement.
10. In a time indicator and in combination with a casing and a motor mechanism, a fixed dial having openings therein, a revolute dial having chronometric indications thereon visible through one of the openings in the fixed dial, a revolute ring also having chronometric indications thereon visible through another opening in the fixed dial, a cannon pinion, a gear associated with the revolute ring, a pinion meshing with the said gear and also with teeth on the revolute dial, a cylinder escapement including a barrel having oppositely disposed recesses therein to permit the passage of the teeth on the gear associated with the revolute ring,

means for driving said cylinder escapement from the cannon pinion, and means for simultaneously actuating the revoluble dial and revoluble ring when the said gear is released by the said cylinder escapement.

11. In a time indicator and in combination with a casing and a motor mechanism, a fixed dial having openings therein, a revoluble dial having chronometric indications thereon visible through one of the openings in the fixed dial, a revoluble ring also having chronometric indications thereon visible through another opening in the fixed dial, a cannon pinion, a gear associated with the revoluble ring, a pinion meshing with the said gear and also with teeth on the revoluble dial, a cylinder escapement including a barrel having oppositely disposed recesses therein to permit the passage of the teeth on the gear associated with the revoluble ring, a train of gears for driving the cylinder escapement from the cannon pinion, a disk, and means also driven by the cannon pinion for simultaneously moving the said revoluble

25 disk and revoluble ring a predetermined portion of a revolution when released by the said cylinder escapement.

12. In a time indicator and in combina-

tion with a casing and a motor mechanism, 30 a fixed dial having openings therein, a revoluble dial having chronometric indications thereon visible through one of the openings in the fixed dial, a revoluble ring also having chronometric indications thereon visible through another opening in the fixed dial, a 35 cannon pinion, a gear associated with the revoluble ring, a pinion meshing with the said gear and also with teeth on the revoluble dial, a cylinder escapement including a barrel having oppositely disposed recesses 40 therein to permit the passage of the teeth on the gear associated with the revoluble ring, a train of gears for driving the cylinder escapement from the cannon pinion, a disk, and a spring connecting the said disk with the said gear associated with the revoluble ring whereby when the said gear is released by the cylinder escapement the revoluble ring and revoluble cylinder are turned a predetermined portion of a revolution.

In testimony whereof I have affixed my signature in presence of two witnesses.

ANDRÉ VARAUD.
